UNITED STATES PATENT OFFICE.

WILLIAM D. BRONSON, OF DUKE, OKLAHOMA.

EXHAUST-HEATER FOR STEAM OR GASOLENE ENGINES.

1,120,996.

Specification of Letters Patent.

Patented Dec. 15, 1914.

Application filed March 27, 1913. Serial No. 757,238.

To all whom it may concern:

Be it known that I, WILLIAM D. BRONSON, citizen of the United States, residing at Duke, in the county of Jackson and State 5 of Oklahoma, have invented certain new and useful Improvements in Exhaust-Heaters for Steam or Gasoline Engines, of which the following is a specification.

My invention relates to devices for heating water, and particularly to means whereby the exhaust from a steam or internal combustion engine may be used for heating water.

The primary object of my invention is 15 to provide a simple, effective, and economical mechanism adapted to provide a base or bed for an engine and so constructed as to provide means whereby the exhaust from the engine may be used for the purpose of 20 heating water.

A further object of the invention is to provide means whereby the exhaust from a steam or internal combustion engine may be carried into a heating chamber and there 25 distributed around water pipes passing through the chamber into which the exhaust is introduced.

For a full understanding of the invention, reference is to be had to the following description and accompanying drawings, in 30 which:—

Figure 1 is a perspective view of my heater applied to an internal combustion engine; Fig. 2 is a longitudinal horizontal section of my heater; Fig. 3 is a vertical section thereof, the interior thereof being shown in elevation; and Fig. 4 is a vertical transverse section on the line 4—4 of Fig. 3.

Corresponding and like parts are referred 40 to in the following description and indicated in all the views of the accompanying drawings by the same reference characters.

As illustrated in the foregoing figures, 2 designates an exterior casing which is closed 45 at one end by an integral web 3 and at the other end is formed with a laterally projecting flange 4, perforated for the passage of rivets to secure a head 14 to the casing. This casing 2 is formed with a base 5 whereby 50 the casing may be supported upon a concrete or brick foundation 6. Mounted upon the casing 2 is a saddle 7 upon which any

suitable engine is adapted to be supported, and to which the bed plate of the engine is bolted.

55

The casing 2 is provided with a water inlet pipe 8 adapted to lead from any suitable source of supply, this pipe being provided with a valve 9. Leading out from the casing is a water outlet pipe 10, also provided with a valve 11. Preferably the water inlet pipe and the outlet pipe are disposed at opposite ends of the casing 2 and at opposite sides thereof. The casing 2 may be, and preferably is, provided with a water 60 gage 12.

65

Disposed within the casing 2, and insertable therein through the end 3 of the casing, is a cylinder 13 of less diameter than the casing 2. This cylinder 13 is closed at one 70 end by means of a head 14, this head being of such size as to close the chamber formed by the casing 2 and to be bolted to the flange 4. Inasmuch as the casing 13 is smaller than the casing 2, a water space will be left entirely around the casing 13, and as the casing 13 is shorter than the casing 2, a water 75 space will be left at the end of the casing.

75

The end of the casing 13 opposite the head 14 is closed by means of a head 15 provided 80 with a plurality of openings 16 from which extend water pipes 17. These pipes extend inward into the interior of the casing 13 and then extend outward and open upon the circumference of the casing 13.

85

Preferably the perforations 16 are arranged in a circular series, and disposed at the center of the circle defined by these perforations is a hollow conical spreader or deflector 18. Entering the head 14 at a 90 point exactly opposite the apex of the deflector 18 is an exhaust pipe 19 having a nozzle. This pipe 19 extends out through the head 14 and is connected by means of an elbow 20 to an exhaust pipe 21 which 95 constitutes the exhaust pipe of the engine. An exhaust outlet pipe 22 extends out of the head 14 and is connected by means of an elbow 23 to any suitable pipe for carrying away the exhaust after it has passed through 100 the chamber formed by the casing 13.

Preferably the water inlet pipe 8 is controlled by means of a float valve 23 actuated by a float 24. This float valve may be of

any suitable construction and is designed for the purpose of admitting water to the space between the casing 13 and the casing 2 when the water within the space has fallen below a certain level, and checking the inflow of water to this space when the water is above a certain level.

The operation of my device is as follows: The exhaust from an internal combustion engine or other suitable motor is carried down the pipe 21 and enters the interior of the casing 13 by means of the nozzle 19. The space between the casing 13 and the exterior casing 2 is filled with water, and it will be obvious that water will also fill the water tubes 17 and the interior of the conical deflector 18. The exhaust is projected by means of the nozzle 19 against the conical deflector 18, and by the deflector is spread uniformly throughout the casing 13 and around the pipes 17. These heated products of combustion after they have passed into the casing 13 are carried away by means of the pipe 22, so that a continuous current of the exhaust is kept up through the casing 13. It will be obvious also that a continuous circulation of water will be secured through the pipes 17 and the jacket surrounding the casing 13, so that every portion of the water will be subjected to the action of the hot products of combustion. The water will be heated not only by its passage through the pipes 17 and by contact with the deflector 18, but also by contact with the head 15 and the wall of the casing 13, the water being carried off through the pipe 10 and used for any suitable purpose.

I do not wish to limit myself to the precise details of construction illustrated, as it will be obvious that many changes may be made therein. Nor do I wish to limit myself to any particular form of engine, as it is readily seen that any engine from which there is a hot exhaust may be used with my device for the purpose of heating water. It is also plain that if my attachments apply to internal combustion engines using liquid fuel, the fuel may be properly heated by passing into the casing 2 and around the inner cylinder or casing 13.

Having thus described my invention, what I claim is:—

1. A heater of the character described including an exterior casing, an interior casing spaced therefrom, an inlet nozzle entering the interior casing, a deflector disposed opposite the nozzle, a pipe for carrying away the exhaust from the interior casing, and means for circulating water between the interior and exterior casings.

2. A water heater of the character described including an exterior casing, an interior casing spaced from the exterior casing to provide a water space between the two, a

plurality of water pipes passing through the interior casing and opening at their ends into the water space, a deflector located at one end of the interior casing, an inlet nozzle entering the interior casing and discharging against said deflector, and means for securing a circulation of liquid between the exterior and interior casings.

3. A heater of the character described including an outer casing, an inner casing spaced from the outer casing to provide a liquid space, a plurality of tubes extending from one end of the inner casing into the interior of the inner casing and opening on the circumference thereof, said tubes being open at the first-named end, a hollow conical deflector disposed at said end of the inner casing, an inlet nozzle projecting into the opposite end of the inner casing and discharging against the deflector, and means for securing a circulation of liquid in the space between the outer and inner casings.

4. A heater of the character described including an outer casing, an inner casing smaller in diameter than the outer casing and having a head at one end adapted to close one end of the outer casing, a plurality of pipes passing through the inner casing and opening at both ends into the space between the outer and inner casings, means for securing a flow of heated products of combustion through the inner casing, and means for securing a circulation of fluid between the outer and inner casings.

5. A heater of the character described including an outer casing, an inner casing forming a closed chamber, one end of the inner casing being provided with a head adapted to close one end of the outer casing, pipes extending through the inner casing and opening at their ends into the space between the outer and inner casings, a conical deflector arranged at the end of the inner casing opposite said head, an inlet nozzle passing through the said head of the inner casing and discharging against said deflector, an outlet pipe leading from said head, and inlet and outlet pipes leading into and out of the outer casing.

6. A heater of the character described including a base, an outer casing mounted upon the base, an inner casing less in length and diameter than the outer casing and having at one end a head of the same diameter as the outer casing and adapted to close the other end thereof, the opposite end of the inner casing being formed with a plurality of openings arranged in a circular series, a plurality of pipes passing through the inner casing and opening at the sides thereof into the space between the outer and inner casings, a hollow conical deflector disposed centrally to said pipes, an inlet nozzle entering the headed end of the inner casing and discharging against said deflector, an

outlet pipe leading from the inner casing, and inlet and outlet pipes leading into and from the outer casing.

7. A heater of the character described including an exterior casing, an interior casing spaced therefrom to provide a water space between the casings, means for introducing heated fluid into the interior casing, means for carrying away the fluid from the interior casing, and a plurality of ducts

disposed within the interior casing and opening each at its ends to the space between the interior and the exterior casings.

In testimony whereof I affix my signature in presence of two witnesses.

WILLIAM D. BRONSON. [L.S.]
